(57) **CLAIM**

The ornamental design for solar light, as shown and described.

DESCRIPTION

FIG. 1 is a perspective view of a solar light showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective exploded view thereof.

The dash broken lines shown in FIGS. 1-2 and 4-8 are included to illustrate portions of the solar light that form no part of the claimed design. The long dash-short dash-short dash broken lines in FIG. 8 are included to illustrate the upward trajectory of the removable panel and form no part of the claimed design. The diagonal shading in a backslash “\” direction shown in FIGS. 1-2 and FIGS. 7-8 indicates a transparent portion.
